(57) **CLAIM**

The ornamental design for a hair straightener, as shown and described.

DESCRIPTION

FIG. 1 is a front perspective view of my new design for a hair straightener. The power cord shown in dotted lines is an unclaimed environmental feature and forms no part of the claimed design.

FIG. 2 is a top plan view of FIG. 1.

FIG. 3 is a bottom plan view of FIG. 1.

FIG. 4 is a left side elevation view of FIG. 1.

FIG. 5 is a right side elevation view of FIG. 1.

FIG. 6 is a front side elevation view of FIG. 1.

FIG. 7 is a rear side elevation view of FIG. 1.

FIG. 8 is a front perspective view of an alternate embodiment of my new design for a hair straightener. The power cord and buttons show in dotted lines are unclaimed environmental features and form no part of the claimed design.

FIG. 9 is a top plan view of FIG. 8.

FIG. 10 is a bottom plan view of FIG. 8.

FIG. 11 is a left side elevation view of FIG. 8.

FIG. 12 is a right side elevation view of FIG. 8.

FIG. 13 is a front side elevation view of FIG. 8; and,

FIG. 14 is a rear side elevation view of FIG. 8.
